2 SHEETS-SHEET 2.

UNITED STATES PATENT OFFICE.

SAMUEL FLOERSHEIM, OF NEW YORK, N. Y.

DIRIGIBLE HEADLIGHT FOR AUTOMOBILES.

1,126,438.

Specification of Letters Patent.

Patented Jan. 26, 1915.

Application filed September 14, 1914. Serial No. 861,536.

To all whom it may concern:

Be it known that I, SAMUEL FLOERSHEIM, a citizen of the United States of America, residing at New York city, borough of Manhattan, county and State of New York, have invented certain new and useful Improvements in Dirigible Headlights for Automobiles, of which the following is a full, clear, and exact description.

10 This invention relates to an improvement in automobiles and relates more particularly to a novel arrangement of the head-lamps. The object of the invention is to provide dirigible head-lights or head-lamps arranged to turn simultaneously with the front wheels in order that the light emitted from the head-lamps will be cast in the direction in which the vehicle is going. For travelling at night this arrangement has a great 20 advantage over the fixed head-lamps; as it will not only show up the road, when rounding a curve, but will also indicate to an on-coming vehicle the direction in which the vehicle, provided with such head-lamps, is 25 turning.

A further feature of my invention is a device whereby the head-lamps can be held stationary at will; hence in the daytime the lamps can be caused to remain fixed regardless of the device for turning them.

I will now proceed to describe my invention in detail, the novel features of which I will point out in the appended claims, reference being had to the accompanying drawings, forming part hereof, wherein:

Figure 1 is a front view of a motor-vehicle equipped with my improvement, certain parts not necessary to my invention being omitted; Fig. 2 is an enlarged sectional view broken away, the section being taken on a line 2-2 in Fig. 1; Fig. 3 is an enlarged sectional detail plan view, the section taken on a line 3-3 in Fig. 2; Fig. 4 is a side elevation of one-half of one of the 40 lamp-support brackets, the view being taken on a line 4-4 in Fig. 3, the lamp spindle and rotatable rod being shown partly in section. Fig. 5 is a sectional plan view, the section being taken on a line 5-5 in Fig. 4; and Fig. 6 is a side view of another form of a lamp locking device.

Referring to the drawing, my invention consists of a plurality of head-lamps 1 and 2 arranged to turn in unison with the turning movement of the front wheels 3 and 4.

To operate the lamps, I preferably connect

them with the cross-rod 5 of the steering-gear, the said rod connecting the steering-arms 6 and 7 on the knuckles 8 and 9.

To support the lamps 1 and 2, I provide 60 bearings 10, one on each frame-member 11 and 12, each bearing being secured to the frame-members in any desirable manner, for instance by the clamp 13. Each bearing 10 rotatably supports two members 14 and 15 65 constituting a rod to turn the lamps. To each upper member 14 I secure a lamp in any desirable manner, the lower member 15 being connected to the cross-rod 5 by an arm 16. The outer end of each arm 16 70 is provided with a hub 17 through which a pin 18, carried by each post-member 15, passes and is adapted to slide therein in a vertical direction. When the cross-rod 5 is located ahead of the axle 19, the post-members 15 will be offset as at 20 to provide an arm to rotate the said post-member, the pin 18 being located at the lower end of the arm 20. Should the cross-rod 5 be located at the rear of the axle the arm 20 75 would be reversed and made to connect with the cross-rod 5. Furthermore when the rod 5 is ahead of the axle, it will move in the direction in which the machine is turning; hence it is necessary to provide the member 80 15 with an arm which extends ahead in order to turn the lamps with the wheels instead of the opposite way. The slip joint at A, consisting of the hub 17 and pin 18 passing loosely therethrough, is provided to allow 85 for the up and down motion of the vehicle upon its springs. Although a complete steering gear is not herein illustrated it will be obvious that the lamps 1 and 2 will turn in the direction imparted to the wheels 3 90 and 4 by the operator of the vehicle.

To steady the lamps I preferably connect them at the tops by a tie-rod 20^a engaging bearings 21 on the top of each lamp. Each bearing 21 is connected by a brace 22 to the 100 aprons 23 of the mud-guards 24. Each lamp 1 and 2 is provided with a pin 25 rotatably supported by its bearing 21. The rod 20^a may be utilized as a license-bracket if desirable. Should I at any time desire 105 to hold the lamps 1 and 2 fixed, particularly during daylight, I provide means whereby the lamp-spindles 14 can be disconnected from the post-members 15.

By referring to Figs. 3 and 4 it will be 110 seen that each bearing 10 consists of two members 26 and 27 connected by bolts 28.

In other words, the bearings 10 are split in order to receive the collars 30 and 31 on the spindle 14 and post-member 15, respectively, the said collars being rotatably seated in recesses or rabbets 29.

When the spindle 14 and member 15 or post-members are locked together the lamps 1 and 2 will turn or rotate whenever the steering wheel (not shown) is operated to 10 change the course of the vehicle.

To lock the post-members together I provide each member, or spindle 14 thereof, with a slot 32 and each post-member 15 with a slot 33 in which a key 34 will slide, 15 the key being operated by a lever 36 pivoted as at 37 in the bearing 10. The arm 38 of the lever 36 is provided with a segment 39 adapted to engage a slot 40 in the key 34, the bearing 10 being provided with a 20 recess or pocket 41 extensive enough to permit the key to travel with the post when said post is rotated. The segment 39 is also long enough to keep in engagement with the slot 40 at all times.

5 When the key 34 is positioned as shown in Fig. 4, the post-members 14 and 15 will be locked together and will turn in unison. Should I desire to have the lamps 1 and 2 remain fixed, I would depress the outer end 0 of the lever 36, thereby raising the key out of the slot 33, in the post-member 15, into the slot 32 in the post-member or spindle 14; at such times the lamps will not turn with the wheels.

5 If desirable the key 34 can be raised to unlock the post-members by means of an electro-magnet 41 acting upon an armature 42 carried by a lever 43 which in turn will 10 actuate the key 34, the magnet being controlled by a push-button on the vehicle.

Having now described my invention, what I claim and desire to secure by Letters Patent is:

1. In dirigible lamp supporting and oper-

ating mechanism for motor vehicles, a lamp 41 supporting and operating rod comprising two members consisting of an upper rotatable spindle and a lower rotatable post member in vertical alinement with said spindle, a key-way formed in said spindle 50 and a co-incident key-way formed in said post member, a locking key slidably mounted in said key-ways and normally locking said spindle and post member together, a lever adapted to operate said key to disengage 55 said spindle and post members, and a lever arm connecting said post member with the cross-rod of the vehicle steering gear.

2. In dirigible lamp supporting and operating mechanism for motor vehicles, a lamp 60 supporting and operating rod comprising two members consisting of an upper rotatable spindle and a lower rotatable post member in vertical alinement with said spindle, a key-way formed in said spindle 65 and a co-incident key-way formed in said post member, a locking key slidably mounted in said key-ways and normally locking said spindle and post member together, electro-magnetic means to disengage said spindle and post member, and a lever arm connecting said post member with the cross-rod of the vehicle steering gear. 70

3. In dirigible lamp supporting and operating mechanism for motor vehicles, a lamp 75 supporting and operating rod comprising two members consisting of an upper rotatable spindle and a lower rotatable post member in vertical alinement with said spindle, and means for releasably locking said members together. 80

Signed at New York city, N. Y. this 10 day of September, 1914.

SAMUEL FLOERSHEIM.
